UNITED STATES PATENT OFFICE.

LUCY JANE GRAHAM, OF NEW YORK, N. Y., ASSIGNOR TO CRANE CO., OF CHICAGO, ILLINOIS, A CORPORATION OF ILLINOIS.

DESIGN FOR A COMBINATION LAVATORY AND DRESSING TABLE.

Application filed May 12, 1928. Serial No. 26,651. Term of patent 14 years.

To all whom it may concern:

Be it known that I, LUCY JANE GRAHAM, a citizen of the United States, residing at New York city, in the county of New York and State of New York, have invented a new, original, and ornamental Design for Combination Lavatory and Dressing Table, of which the following is a specification, reference being had to the accompanying drawing, forming part thereof.

In the drawing:

The figure is a perspective view of the article showing my new design.

I claim:

The ornamental design for a combination lavatory and dressing table as shown.

In witness of the foregoing I affix my signature.

LUCY JANE GRAHAM.
